UNITED STATES PATENT OFFICE.

ALCORN RECTOR, OF NEW YORK, N. Y., ASSIGNOR TO RECTOR GAS LAMP COMPANY,
OF NEW YORK, N. Y., A CORPORATION OF NEW YORK.

DESIGN FOR A GAS-LAMP.

No. 39,406.

Specification for Design.

Patented July 7, 1908.

Application filed October 24, 1907. Serial No. 399,057. Term of patent 14 years.

To all whom it may concern:

Be it known that I, ALCORN RECTOR, a citizen of the United States, residing in the city, county, and State of New York, have invented a new, original, and ornamental Design for a Gas-Lamp, of which the following is a specification, reference being had to the accompanying drawings, forming part thereof.

The figure is a side elevation of a gas lamp showing my design.

I claim:

The ornamental design for a gas lamp as shown.

ALCORN RECTOR.
